UNITED STATES PATENT OFFICE.

HARRY L. GARRETT, OF BOONE, IOWA.

FASTENER FOR VESTIBULED-CAR CURTAINS.

No. 839,576.

Specification of Letters Patent.

Patented Dec. 25, 1906.

Application filed November 24, 1905. Serial No. 288,890.

To all whom it may concern:

Be it known that I, HARRY L. GARRETT, a citizen of the United States, residing at Boone in the county of Boone and State of Iowa, 5 have invented certain new and useful Improvements in Fasteners for Vestibuled-Car Curtains, of which the following is a specification.

My invention relates to improvements in 10 fasteners for vestibuled-car curtains. These curtains are used to cover the inner sides of the passage-way of vestibuled cars to prevent accidental injury to passengers and to present a more finished appearance. One end of 15 the curtain is usually hung upon a spring-roller, the latter being mounted vertically upon one car-platform, the opposite end of the curtain being mounted upon a curtain-pole and stretched to the platform of an adjacent car, to which this pole is fastened. Various devices have been employed to effect a 20 fastening of this curtain-pole. When the cars are detached, the employee often forgets to manually unfasten the curtain, the result 25 being a breakage of the parts. Automatic means for disconnecting the curtain have heretofore been presented, but have not gone into use because of complex and expensive construction.

30 The object of this invention is to present more simple, durable, and less expensive fasteners than heretofore constructed which will effectually hold the free end of curtains.

With these objects in view the invention 35 presents a novel construction and arrangement of parts, as described and claimed and as illustrated in the drawings, wherein—

Figure 1 represents a vertical elevation of the invention in operative position, this being 40 a view from the inner side of the vestibule. Fig. 2 represents a vertical side view of the invention mounted upon a curtain-pole and attached to the hook of the car. Fig. 3 is a modified view of Fig. 2, showing a detached position of the fastener. Fig. 4 is a 45 vertical end view of the device to show relative position of parts; and Fig. 5 represents a sectional view of the curtain-pole, being upon the line *a b* of Fig. 4, to show the arrangement of certain parts of the invention.

I construct the frame represented by the 50 numeral 1, having the pivot-bearing arms 2 and the clips 3 and 4 constructed integrally thereon, said frame 1 being longitudinally disposed upon the curtain-pole 5, the clips 3 and 4 extending transversely from the frame,

encircling pole 5 and secured upon the latter by means of screws 6. The clip 4 is extended beyond its junction with frame 1 to provide the rectangularly-formed plates or arms 7 and 8, Fig. 5, these arms being parallel and occupying the same planes with reference to their transverse position upon the frame, and between arms 7 and 8 is pivotally mounted at 9 the lever 10. Lever 10 is provided with an arm 11, which extends between the free ends of arms 7 and 8, parallel with the frame 1 and pole 5, to a point beyond the outer perimeter of these arms, from which point said lever-arm 11 extends in a direction substantially parallel with the outer walls of arms 7 and 8 toward the pole 5, this portion being indicated by the numeral 12, and a portion of said lever-arm extends, as indicated by 13, to a position upon that side of the pole opposite frame 1 and there terminates in the eye 14, and to the latter is attached the chain 15, having a less length than curtain 29.

In alinement with the outer face of frame 1, integrally upon clip 4 and between arms 7 and 8, is constructed suitable lugs 16 and 17, between which is seated the coiled spring 18, which makes contact with lever 10, Figs. 2, 3, and 5, and pivotally mounted at 19 within pivot-bearing arms 2 is mounted the holding-bar 20. The numeral 21 represents the post or casing of a car, upon which is rigidly mounted the hook 22, over and upon which the rod 20 is adapted to pass. The holding-rod 20 is chamfered upon its free end to 50 form the angularly-faced recess 23, within which the lug 24 of lever 10 is adapted to enter, as shown by Fig. 2. Upon casing 25 of an adjacent car, within suitable bearings 26, is pivotally mounted at 27 the curtain-roller 28, the latter being provided with a well-known coiled spring (not shown) and exerting a constant tension upon the stretched curtain 29, and upon casing 25 at 30 is securely mounted one end of chain 15.

From the description thus given the construction and operation will be understood. The parts are purposely made as few as possible consistent with effective operation. The hook 22 substantially as shown is already in 105 general use upon vestibule-cars. The holding-rod 20 when inclosed within the hook is adapted to move vertically thereupon, which corresponds to the vibrating movement of the car-platform when cars are in motion. 110 The clips 3 and 4, as shown, are adapted to be readily fastened upon curtain-poles al-

ready in use. It is believed that the mounting of the holding-bar should be vertical, as here shown, to obtain the best results, and the use of the portions 11, 12, and 13 to form the lever-arm which coacts with the holding-bar is a very convenient, efficient, and economical construction.

In operation curtain 29 is stretched from the end of one car to another, its length being ample for this purpose. The bar 20 is then passed over hook 22 and locked upon lever 10. The curtain then remains in a drawn position while in use. At the time of separation of the cars no attention is given to the curtains with a view to their release, for since chain 15 has a less length than the curtain when the cars separate lever 10 under operation of the chain releases the bar 20 from hook 22, this action taking place before any undue strain is exerted upon the curtain.

What I claim as my invention is—

1. The combination of a curtain and cable for vestibuled cars mounted upon the vestibule-frame of one car, a curtain-hooking member seated upon another car, a locking-bar pivotally mounted upon one end of said

curtain and adapted to engage said curtain-hooking member; a lever upon said curtain adapted to control said pivotally-mounted locking-bar; the opposite end of said cable mounted upon said lever whereby the locking-bar will have a rotative movement by the separation of the cars.

2. The combination of a detaining member upon one car; a curtain and flexible member upon another car; said flexible member being of less length than said curtain; a suitable frame 2 adapted to sustain the mechanism mounted thereon; said frame being mounted upon said curtain and provided with the clips 3 and 4; the resiliently-actuated lever 10 provided with the lever-arms 11, 12 and 13, and pivotally-mounted locking-bar 20, substantially as shown and described.

In testimony whereof I have affixed my signature in presence of two witnesses.

HARRY L. GARRETT.
